UNITED STATES PATENT OFFICE.

WILLIAM A. SLATTER AND JAMES J. KINDELL, OF COLUMBUS, OHIO.

FOLDABLE PORCH-SWING.

1,146,358.

Specification of Letters Patent. Patented July 13, 1915.

Application filed February 18, 1913. Serial No. 749,212.

To all whom it may concern:

Be it known that we, WILLIAM A. SLATTER and JAMES J. KINDELL, citizens of the United States of America, and residing at 5 Columbus, in the county of Franklin and State of Ohio, have invented certain new and useful Improvements in Foldable Porch-Swings, of which the following is a specification.

10 Our invention relates to seats or benches but is particularly applicable to porch swings of the type comprising a suspended bench whose main claims to novelty are dependent upon and arise from the fact that 15 it is a foldable porch swing in contradistinction to those of the knockdown type.

As far as we are aware, there has been no porch swing yet built which is practical for every-day use and practically foldable.

20 The difficulty has seemed to mainly reside in the fact, that to produce a comfortable bench, the back must be inclined away from the base or seat. This is apparently simple enough until it is remembered that there 25 must be provided arm-pieces and that these arm pieces should fit the obtuse angle formed between the back and base. It is just at this point that the obstacle arises for the reason that any arm-piece which

30 fits this obtuse angle has inner corners which are not right angles. Yet, both the base and back should be rectangular in form and usually are so in the attainment of the most reasonable and most compact construction.

35 If the arm-pieces are hinged to the back in the normal manner so that they may fold outside of the upwardly folded base, the obtuse angles of the lower inner corners of the said arm-pieces are of course greater 40 than the right angular lower corners of the back and, in consequence, the lower outer corners of the arm-pieces must protrude below the lower edge of the back. As a result, whenever the folded seat is set down it will

45 rest upon these protruding points and the hinges of the arm-pieces will either be severely strained or broken. If the arm-pieces are hinged to the base by normal hinges, the same thing would occur in that 50 there would be protruding corners, unless the bench structure were varied from the

sane simplicity that is giving general satisfaction today.

Our invention resides in the provision of a bench that may be folded into compact 55 form without necessitating removable bolts, and without necessarily varying from that most desirable type of bench with substantially rectangular back and base forming an obtuse angle and having arm-pieces 60 fitting such angle. We have made this feasible by so mounting the arm pieces that they may fold to a position within the circumference of the back. As a matter of fact, we have provided such a hinge structure 65 that the arm-pieces cannot drop below the lower edge of the back for the reason that the very structure of the hinge limits such downward swinging when the arm pieces are in folded position, although the 70 hinge structure is at the same time effective to permit of re-alinement of the arm-pieces so that they may rest flat against the up-folded base.

Our invention further consists in the provision 75 of means for relieving the strain which would otherwise fall upon the hinges when the arm-pieces are folded, this means being further effective to lock the parts of the bench in folded position. 80

Another feature of importance in our invention resides in the means for locking the parts together when they are in extended or operative position, the form of this locking means being such that natural strains upon 85 the bench only tend to make the locking action more sure.

The preferred embodiment of our invention is shown in the accompanying drawings in which similar characters of reference 90 designate corresponding parts and in which:

Figure 1 is a front elevation of the bench of our porch swing in position for use. Fig. 2 is a plan view of the bench in the position shown in Fig. 1. Fig. 3 is a front 95 elevation of the bench in folded position, showing in dotted lines what the position of the arm-pieces would be if the normal manner of hinging were used. Fig. 4 is a detail showing our compound hinge structure 100 in side elevation and partial section. Fig. 5 is a detail in front elevation of this com-

pound hinge together with the adjacent parts of the bench.

In the drawings, the bench of the swing is shown as comprising a back and base, respectively designated 1 and 2, which are connected at their juncture by pivots 3. The seat or base may be maintained practically horizontal while the back is inclined away from vertical so that the angle between the base and the back is obtuse, which has been found to be the most desirable for comfort. The base or seat carries upon its ends near the front edge or free edge thereof angle hooks 4 for a purpose to be described.

At the center of the back and near the lower edge thereof we have placed a bracing element 5 to partially support the center of the seat or base and to prevent sagging at this point. At either end of the back 1 are mounted arm-pieces 6 in a manner best shown by Figs. 4 and 5 of the drawings. The essential feature of this mounting consists in a compound hinge of peculiar type, it being comprised of leaves 7 and 8 connected by a pivot pin 9 adapted for horizontal disposition and a plate 10 having a vertical pivot stud 11 serving as a complement thereto. The leaf 7 is secured to the back 1 by screws 12 while the leaf 8 is apertured for the reception and working retention of the headed pivot stud 11 which is secured to the upper edge of the arm-piece through the medium of screws 13 passing through the plate 10 which carries such stud. It is thought that the action will be apparent. The arm-piece may be swung outwardly and upwardly about the horizontal axis of the pivot pin 9 and then may be swung laterally about the vertical axis of the pivot stud 11. The lower inner end of each arm-piece may be braced by means of a dowel pin 14 carried by the back and fitting in a socket 15 in the arm-piece while the front end of the arm-piece is provided with a loop socket 16 for the reception of the hook 4.

In operation, the bench when in position for use has the arm-pieces supported at their upper rear ends by the compound hinges and at their lower rear ends by the dowel and socket fittings. At the lower forward ends, the hooks 4 fit in the loop sockets 16 and the sides are not only braced against laterally outward movement and against laterally inward movement but the more weight is applied to the seat or base, the more firm becomes the locking or bracing action.

To fold the bench, the seat or base is swung upwardly against the back. Then the arm-pieces are swung outwardly and upwardly about their horizontal pivots until the dowel pins are cleared, when they are swung laterally upon their vertical pivots. The result obtained in this lateral swinging is not so apparent at first glance but we de-

sire to especially point out that the arm-pieces, though lifted initially above what would seem to be their natural positions, cannot return to such natural positions after the lateral movement has once begun. The arms cannot sag because the pintle 9 and the plate 8 have no possible movement in that direction. At any rate, the very swinging of the arm-pieces laterally prevents them from dropping at their outer ends and consequently prevent the lower outer corners of the arm-pieces from protruding. At the same time, the horizontal pivots of the leaves permit the said arm-pieces to assume a plane substantially parallel with the base and back. Now, though the hinges alone will maintain the arm-pieces within the circumference of the back, we deem it well to obviate the strain, however slight, by the provision of hooks 17 upon the under side of the seat or base and upon which the arm-pieces are hung. These hooks serve a double purpose for they not only assist in supporting the arm-pieces but they lock the back, base and arm-pieces together as a unit, so that transportation can have no ill effect upon the swing when folded.

The swing bench may be suspended in any manner as by hooks 18.

It will be understood that the showing in the drawings is mainly for the purpose of more clearly setting forth the principles of our invention and that the structural features may vary.

Having thus described our invention, what we claim as new and desire to secure by Letters Patent, is:

1. A folding seat comprising a base, a rectangular back hinged to and forming an obtuse angle with said base, and arm-pieces constructed to fit such obtuse angle and mounted to permit swinging to folded position within the periphery of the folded base and back.

2. A folding seat comprising a base, a rectangular back hinged to and forming an obtuse angle with said base, arm-pieces constructed to fit such obtuse angle, and hinges of such a form that said arm-pieces during folding are positively brought within the periphery of the folded base and back.

3. A folding seat comprising a base, a back forming an obtuse angle with said base, arm-pieces constructed to fit such obtuse angle, and hinges for connecting such arm-pieces to the seat and whose elements comprise horizontal and vertical pivots so disposed that said arm-pieces may swing to folded position within the periphery of the folded base and back.

4. A folding seat comprising a base, a back forming an obtuse angle with said base, arm-pieces constructed to fit such obtuse angle, and compound hinges connecting said arm-pieces to said back, each hinge comprising

a plurality of pivots substantially at right angles to each other.

5. A folding seat comprising a base, a back forming an obtuse angle with said base, arm-pieces constructed to fit such obtuse angle, compound hinges connecting said arm-pieces to said seat at one corner thereof, said hinges being of a form to permit said arm-pieces to swing to folded position within the periphery of the folded base and back, means for

bracing the other corner of said arm-pieces, and means for connecting the free ends of the arm-pieces to the seat.

In testimony whereof we hereby affix our signatures in presence of two witnesses.

WILLIAM A. SLATTER.

JAMES J. KINDELL.
